RODDING ATTACHMENT FOR PLASTIC BLOCK MACHINES

Frank C. George, Orlando, Fla., assignor, by
mesne assignments, to F. C. George Machine
Company, Orlando, Fla., a corporation of
Florida

Application April 29, 1946, Serial No. 665,776

2 Claims.

(Cl. 25—41)

1

This invention is concerned with the provision of a simple practical pressure attachment for plastic block machines, for use in the settling and compacting of the plastic in the block mold.

Broadly it is an object of this invention to provide a pressure attachment for plastic block machines of the type which consists generally of a tubular frame member rigidly attachable in a vertical position to the block machine, oppositely disposed and spaced bracket members vertically slidable upon the upright portions of said frame, a pressure rodding foot interposing said vertical bracket members and rigidly suspended from a bracket spacing rod, and leverage means arranged in such manner as to vertically actuate said bracket and pressure foot carried thereby for contact of said foot with the plastic in the mold and to exert leverage upon said foot for submitting a cutting pressure upon the plastic in the mold box to shatter air-pockets and the like in the plastic thereby aiding densification of the material comprising the blocks, and hoisting means for releasing said pressure foot from the mold when pressure thereon is released.

This invention resides substantially in the combination, construction, arrangement and relative location of parts, all in accordance with the disclosure herein.

In the accompanying drawings.

Figure 1 is a partial front elevation of a plastic block machine and illustrating an adaptation of my invention thereto.

Figure 2 is an end elevation thereof.

Figure 3 is a partial section illustrating my invention during a pressing operation.

Figure 4 is a plan view with the block machine omitted and the hand lever shown in dash lines for clearness of illustration.

The true nature and manner of use of a device in accordance with this machine will be best understood by a detailed description of the form thereof shown in the drawings in an illustrative sense.

Now referring more particularly to the drawings A designates generally a plastic block machine having a mold box with cores therein, a plastic container or hopper, and a pan for deposit from the hopper of plastic and delivery of same to the mold box, which may be of a conventional make, preferably of a type wherein, during operation thereof, there is a vibrating action in the mold for settling and compacting the plastic, however, this is not to be considered as a limitation as the function of this device is of extreme value in combination with a machine wherein both the

mold box and cores are fixed. Forming a part of the structure of this invention is a tubular frame 2 having parallel spaced uprights and a spacing head adapted to be disposed vertically to and rigidly engaged with the block machine at opposite sides thereof as indicated in the drawings or such other means as the type of machine to which attachment is made demands, and centered to the mold box to assure entry of the pressure foot therein.

One purpose of said frame is to provide a guide for the vertical raising or lowering of the pressure foot which comprises one or a series of units such as designated by 3, of any desirable shape such as square, rectangular, or round, and if used in a mold box having a core as illustrated in the drawings and herein described, same is hollowed to render it circumambient to the core and for spacing from the core and inner vertical faces of the core box to permit for cutting of same into the plastic in the mold box to shatter air pockets or the like, during downward pressure thereof said units being horizontally carried at the lowermost end of the spindles 4 and rigidly fixed thereto, upper ends of said spindles being in rigid engagement with a horizontal frame 5 which is in turn carried by a bracket member comprising vertical rods 6 disposed parallel with and to the rear of the upright members of the frame 2 and spaced by transverse rod 7; which carries horizontal frame 5 laterally thereto and head and base members 8 and 9 respectively fixedly engaged upon opposite ends of the rods 6 and collaring the frame upright members for guided 35 sliding engagement of the bracket therewith.

Lever actuating means for the device is provided by hand levers 10 having effectual pivotal points, for example, as shown at 11, and extended therefrom to the front of the machine with points 40 of fulcrum upon rollers 12 which have bearing upon the rod 7. Although two levers are shown and described this is not to be considered as a limitation as the actual value of the extra lever is in the provision of even distribution of leverage 45 pressure.

Observation of the drawings will teach that there is formed on the under edge of the hand lever a hook member 14 for contact with the under surface of the rollers 12. There are times when a unit 3 will become momentarily lodged in the plastic during a pressing operation and to such extent that the hoisting mechanism in the form of a counterweight 15; which will ordinarily hoist the pressing mechanism when pressure thereon 50 is released; is unable to properly function, under

such condition the hand levers are raised and thru contact of said hook member 14 with the roller 12 the pressing mechanism is urged upward releasing the pressing unit and allowing the hoisting mechanism to perform its normal function.

From the above description it will be apparent to those skilled in the art that the details of construction illustrated herein may readily be varied without departure from the novel subject matter herein disclosed. I do not therefore desire to be limited by the disclosure but rather by the claims granted me.

What is claimed is:

1. A rodding attachment for a plastic mold machine having a settling and compacting mold supported on a base, vertical rods in opposite sides of the base, a rodding foot, having a cutting edge, movable toward and away from the mold, a movable support carrying the foot and a runner bracket on the support arranged to slide on the vertical rods for guiding it in a vertical path toward and away from the mold.

2. A rodding attachment for a plastic mold machine having a settling and compacting mold

supported on a base, vertical rods in opposite sides of the base, a rodding foot, having a cutting edge, movable toward and away from the mold, a movable support carrying the foot, a runner bracket on the support arranged to slide on the vertical rods for guiding it in a vertical path toward and away from the mold, a roller on the bracket, an arcuately swingable lever pivoted for vertical movements and riding upon the roller to effect pressure on the bracket during the lowering of the latter, and a track extension on the lever beneath the roller for its travel thereon during the raising of the bracket and exerting pressure on the roller when the said bracket is raised.
